UNITED STATES PATENT OFFICE

2,055,344

JAR HOLDER

Louis Fiedler, Detroit, Mich.

Application May 1, 1935, Serial No. 19,213

1 Claim. (Cl. 81—3.3)

My invention relates to a new and useful improvement in a jar holder adapted for holding fruit jars and the like while the screw cap to the same is being tightened or removed.

It is an object of the present invention to provide a means whereby a fruit jar may be held so that an easy and quick placement of the cap may be effected.

Another object of the invention is the provision of a device of this class which will be simple in structure, economical of manufacture, durable, and highly efficient in use.

It is another object of the invention to provide a jar holder of this class so arranged and constructed that while it will tightly grip the jar in position and prevent its rotation, it will also so grip it as to minimize the danger of fracturing the same.

It is another object of the invention to provide a jar holder of this class which may be easily and quickly adjusted to jars of different sizes.

Another object of the invention is the provision of a jar holder which may be used for clamping, against rotation, jars which are circular in cross section or which are formed with flat faces.

Other objects will appear hereinafter.

The invention consists in the combination and arrangement of parts hereinafter described and claimed.

The invention will be best understood by a reference to the accompanying drawing.

Fig. 1 is a top plan view of the invention.

Fig. 2 is a side elevational view of the invention with a part broken away and a part shown in section.

Fig. 3 is a sectional view taken on line 3—3 of Fig. 1.

Fig. 4 is a fragmentary sectional view taken on line 4—4 of Fig. 1.

Fig. 5 is a top plan view of a separable gripping member with a part broken away and a part shown in section.

Fig. 6 is a fragmentary sectional view taken on line 6—6 of Fig. 5.

Fig. 7 is a top plan view of a tightener with parts broken away and shown in section.

The invention comprises a base or supporting plate 10 which is formed from any suitable rigid material. Covering the upper surface of this base or supporting plate 10 is a layer 11 of yieldable material such as rubber or the like. This layer 11 has the inwardly directed flange 12 around its edges so that the covering plate 11 may be snapped over the supporting plate 10, 55 and projecting upwardly therefrom, through

openings formed in the cover 11, are retaining studs 13 and 14. Secured to the plate 10 and projecting downwardly therefrom are non-abrasive feet 15 which are preferably formed from rubber or other suitable material. Extending downwardly from the front side of the plate 10 are abutment plates 16 which are adapted to engage the edge of the table or other suitable support on which the device is fastened. Projecting downwardly from the forward end of the plate 10 is the arm 17 of a screw clamp in which is rotated the screw 18 having the engagement shoe 19. The rod 20 serves as a handle. By this means the plate 10 may be securely clamped to a table or other suitable supporting surface such as a board or the like with the feet 15 engaging the upper surface of the supporting structure. The abutment plate 16 serves to prevent the turning of the plate as the screw 18 is forced into clamping engagement against the supporting structure.

Swingably mounted by means of the rivet 21 on the plate 10 is a clamping arm 22, this arm being pivoted intermediate its ends. An upwardly turned, angularly directed end portion 23 terminates in the handle 24 which is spaced above the plate 10. Pivotedly connected at one end to the clamping arm 22 is a connecting rod 25 which threads into the turn buckle 26. A connecting rod 27 also connects into this turn buckle 26 at one end and the opposite end of the rod 27 is pivotally connected to the boss 28 which is mounted on the metallic band 29 which is preferably formed from spring material. Secured to the outer surface of the band 29 are eyelets 30 and 31 which embrace the studs 13 and 14, respectively, and serve to anchor the clamping band at one end. Fixed on the inner surface of the band 29 is a layer 32 of yieldable material such as rubber, leather or the like, to serve as a gripping member for gripping the periphery of a jar.

In operation the handle 24 would be swung to the dotted line position shown in Fig. 1 which would effect an expanding of the circle formed by the band 29. A jar may then be positioned on the covering 11 within the band and upon a swinging of the handle 24 to the full line position the band will be brought into clamping relation with the jar so as to securely clamp the same by the lining 32 and holding the jar against rotation. It will be noted that in this swinging movement from the dotted line to the full line position in Fig. 1 the pivot of the end of the member 25 is swung past center so that the device is locked in clamping position and the jar 55

will be held in fixed relation until the handle is again swung past center towards the dotted line position. When clamped in this position the cover of the jar may be easily and quickly placed in position and to this end I have provided a simple gripping member for gripping the cover of the jar. This merely comprises a spring wire or similar material doubled upon itself to provide the circular loop 33 terminating in the parallel arms 10 34 and 35. The loop and arms are covered with a layer 36 of rubber or the like, as illustrated in Fig. 7.

When the clamping member and the cover tightener are used it is obvious that the screw cap of a fruit jar or the like may be placed thereon while the contents of the jar are raised to a high temperature without necessitating the operator placing his or her hands upon the hot jar. This will afford a means for securely tightening the cap in position and at the same time so facilitate the operation as to result in a considerable saving of time.

The structure shown in Fig. 1 is primarily adapted for use on cylindrical jars, it may, however, be used with flat faced jars but its efficiency would be considerably less with such structures than with the cylindrical jars. Accordingly I have provided an attachment which may be easily and quickly placed in position to accommodate the device for use with flat faced jars. This attachment consists of a lining 37 formed from rubber and the like and having a circular peripheral surface 38 so that it will lie, when in position, in snug engagement with the inner surface of band 32. The inner surface of this liner 37 is provided with the flat faces 39 so that the inner surface of this attachment liner conforms to the periphery of a flat faced jar. Imbedded at spaced intervals in the attachment liner 37 are wire hooks 40 having the outwardly spaced, downwardly extended legs 41 which will serve to

hook over the upper edge of the band 29 and the liner 32 so that the device may be very easily and quickly changed from a device intended for use with round or cylindrical jars to the device adapted for use with flat faced jars.

It will be noted that the band 29 is detachably mounted upon the support plate 10 and may be easily and quickly removed when desired. The turn buckle also affords a means for adjusting the band to various sizes to accommodate jars 10 of various sizes.

While I have illustrated and described the preferred form of construction I do not wish to limit myself to the precise details of structure shown but desire to avail myself of such variations and modifications as may come within the scope of the appended claim.

Having thus described my invention, what I claim as new and desire to procure by Letters Patent, is:

A device of the class described, comprising: a supporting plate; a pair of spaced studs projecting upwardly from the upper face of said plate; a clamping band curved to define a circle; a pair of spaced eyelets projecting outwardly from the periphery of said band, adjacent one end, and slidable over said studs in embracing relation, said studs being located on the arc determined by said band, said band upon the slipping of said eyelets over said studs, resting upon the upper face of said plate; a yieldable liner on the inner face of said band; a handle pivotally mounted, intermediate its ends, on the upper face of said plate, one end of said handle being upwardly offset from said plate; and means for connecting the opposite end of said handle to the free end of said band for effecting an expansion and contraction of said band upon the pivotal movement of said handle, dependent upon the direction of movement.

LOUIS FIEDLER.
